DESIGN FOR A SCOOTER

Wilbur Henry Adams, Cleveland, Ohio, assignor to The Colson Corporation, Elyria, Ohio, a corporation of Ohio

Application July 21, 1937, Serial No. 70,561

Term of patent 3½ years

To all whom it may concern:

Be it known that I, Wilbur Henry Adams, a citizen of the United States, residing at Cleveland, in the county of Cuyahoga and State of Ohio, have invented a new, original, and ornamental Design for Scooters, of which the following is a specification, reference being had to the accompanying drawing, forming part thereof.

I claim:

The ornamental design for a scooter, substantially as shown.

WILBUR HENRY ADAMS.
